UNITED STATES PATENT OFFICE.

DAVID L. LINDQUIST, OF HARTSDALE, NEW YORK, ASSIGNOR TO OTIS ELEVATOR COMPANY, OF JERSEY CITY, NEW JERSEY, A CORPORATION OF NEW JERSEY.

ELEVATOR SAFETY APPLIANCE.

Application filed July 11, 1924. Serial No. 725,428.

To all whom it may concern:

Be it known that I, DAVID L. LINDQUIST, a subject of the King of Sweden, residing in Hartsdale, in the county of Westchester 5 and State of New York, have invented a new and useful Improvement in Elevator Safety Appliances, of which the following is a specification.

This invention relates to safety devices 10 for the parts of an elevator system traveling in the hatchway, and particularly to safety brakes adapted to be applied to a stationary rail for bringing the moving parts to a stop in the event of their traveling above a pre- 15 determined speed.

One object of the invention is to apply a substantially constant retarding force in predetermined amount to bring the moving parts to a stop whenever the safety device 20 is actuated.

Another object is to provide such a safety brake which, after it has been applied to stop the moving parts, will be released upon their being moved in the reverse direction,

25 A further object is to provide, in an elevator system equipped with buffers at the end of travel of the moving parts, means for preventing the simultaneous operation of the safety brake and buffers to stop the 30 moving parts.

Other objects will appear from the specification and claims.

In a preferred embodiment of the invention the safety brake, which is mounted on 35 the elevator car, has a pair of rollers disposed on opposite sides of the guide rail and arranged to be brought into rolling contact with the guide rail when the safety brake is applied. A yielding member is employed 40 between each roller and the rail to exert a pressure between them and at the same time resist rotation of the roller about its axis. The amount of such pressure is automatically regulated by an adjustable resilient 45 force acting substantially parallel to the rail, and this resilient force determines the retarding effort. The organization of parts is such that when the car has been brought to rest by the safety brake, it can be started 50 again in the opposite direction by the hoisting mechanism, without the necessity of first manually disengaging the parts of the safety brake from the rail. Where buffers are employed, as for example in the elevator pit,

to stop the elevator car at the limit of its 55 downward movement, occasion may arise when the safety brake will be acting to stop the car at the time that it strikes the buffer. In such event the retardation of the car will be too rapid due to the action of both 60 the buffer and safety brake, so that passengers may be injured and the equipment damaged. To avoid this the thickness of the rail is decreased at points in the hatch 65 where both the buffer and safety brake might 70 act simultaneously so that the safety brake cannot be applied at these points to stop the car.

An embodiment of the invention wherein a safety brake is carried by the car and 75 buffers are mounted in the elevator pit is described in connection with the accompanying drawings, in which,—

Figure 1 is a schematic view of an elevator system to which safety devices in 75 accordance with this invention are applied,

Figure 2 is a front elevation on a larger scale of a portion of the rail used in the elevator system shown in Figure 1,

Figure 3 is an end elevation of the safety 80 brake in released position, with certain parts removed, and shows the operating mechanism therefor,

Figure 4 is an elevation of the safety brake 85 in applied position,

Figure 5 is a detail view of one of the engaging rollers of the safety brake, and

Figure 6 is a sectional view taken on line 6—6 of Figure 3.

Referring to Figure 1, the elevator system 90 includes the car 10 which is suspended by cables 11 extending over a driving drum 12 to counterweight 13. The drum 12 is driven by a motor 14 and has an electromagnetic brake 15. Stationary guide rails 95 16 are provided in the hatchway and the car 10 has an upper set of guide shoes 17 and a lower set of guide shoes 18. The thickness of the guide rails is decreased below the point 19, Figure 1, in the manner shown in Figure 2 for a purpose to be hereinafter pointed out. Buffers 21, indicated as oil buffers in Figure 1, are provided in the elevator pit for bringing the car to a stop in the event that the car passes too 100 far below the lower landing 20.

The safety brakes 24 are mounted one on each end of the safety plank 22 which is

secured to the bottom of the car. Safety plank 22 supports a pair of shafts 23 which operate upon safety brakes 24 to cause them to engage the guide rails.

As best shown in Figure 3 shafts 23 are connected by a pair of gears 25 so as to be rotated together and a bevel driving gear 26 secured to a shaft 27 meshes with a corresponding bevel gear formed on the back 10 of one of gears 25. Shaft 27 is supported from the bottom of the car 10 by two hangers 28 and 29 and it is provided with a torsion spring 30 which tends to hold it in the position shown in Figure 1. Shaft 27 also 15 has a lever arm 31 to which is attached a rope 32.

Referring again to Figure 1, rope 32 extends over a guide sheave 33 supported from the bottom of car 10 adjacent to one 20 side thereof, and from there rope 32 extends upwardly to hitch 34 on governor rope 35. Hitch 34 is normally held in a releasing carrier 51 attached to the car. Governor rope 35 extends from hitch 34 over a sheave 36 25 of a centrifugal governor and thence around tensioning sheave 38 which has a weight 39 mounted in guides 40.

Upon excessive speed of the car, a set of 30 jaws 41 and 42 are tripped so as to engage the governor rope. Jaws 41 and 42 have a gear connection between them so that they will operate together. Jaw 41 is pivoted at 35 43, and is provided with an arm 44 to which a link 45 of the governor is operatively attached. A spring pressed latch 46 engages the end of arm 44 until such a time as the governor reaches the speed for which it is adjusted to act, whereupon latch 46 releases the arm 44. When arm 44 is released link 40 45 raises arm 44 so as to close jaw members 41 and 42 upon the governor rope 35 and thus stop its movement. Jaw 42 is pivotally mounted at 47 on a rod 48 which is slidably carried in a guide support 49 and provided 45 with a spring 50 which urges the jaw 42 into engagement with the governor rope 35, but allows rope 35 to slide through the jaws when the tension exceeds an amount determined by the pressure of spring 50. When 50 the governor acts, due to overspeed of the car in the down direction, hitch 34 is withdrawn from releasing carrier 51 and as the elevator descends a tension is exerted on rope 32 to apply safety brake 24 to rails 16.

Referring to Figure 3 the safety plank 22, upon which safety brakes 24 are mounted, comprises two channels 55 and 56 secured in spaced relation by means of upper and lower plates 57 and 58 respectively. Abutments 59 are secured to the channels at their ends on opposite sides of the guide rail 16, and are provided with lower projections 60 for guiding the actuating rods 67 and with upper projections 61 for taking the upward 65 thrust of jaw members 52 and 53.

Between each of jaw members 52 and 53 and its abutment 59 are a pair of links 62, the ends of which are rounded and fit in corresponding concave bearings formed in abutments 59 and jaw members 52 and 53, 70 as will be best seen in connection with jaw 52, when the side plates are removed. These links take the outward thrust of the jaws and allow them to swing upwardly against the action of springs 63. The latter are 75 mounted between the upper surfaces of jaws 52 and 53 and the projections 61 and in the released position of the safety brake act upon the jaw members to hold their lower ends in engagement with projections 60. Adjusting screws 74 serve to regulate the pressure exerted by springs 63.

In connection with jaw 53 (see also Figure 6) a side plate 65 is shown secured on each side of abutment 59, by screws 75. 80 These side plates overlap the ends of links 62 and have pivotal connections thereto by pins 66. Similarly side plates 64 are secured to jaw 53 and have pivotal connections with links 62 by pins 76. These side plates hold the parts in assembled relation but are not called upon to transmit thrust between jaw 53 and abutment 59.

Jaws 52 and 53 are oppositely cut away on the two sides of guide rail 16, so as to 95 form cam surfaces 77 which slope upwardly toward the guide rails with a considerable angle for a portion of their length and a small angle for the balance of their length. Stops 78 are provided at the upper ends of the cam surfaces. Rollers 54 are rotatably mounted between the arms of forks 68 on pins 79. Forks 68 are pivotally carried on actuating rods 67 by pins 80, (see Figure 5). Actuating rods 67 pass upwardly 100 through the lower projections 60 on abutments 59 and carry the rollers in the space provided between cam surfaces 77 and rail 16. In the released position of the safety brake (Figure 3) the rollers are held away 110 from the surfaces of the guide rail 16 by means of fixed roller guides 69 secured to the lower projections 60. Compression springs 70 on rods 67, between a boss on roller guides 69 and heads 71 on the lower ends of the rods, tend to keep the rods and rollers in the position shown in Figure 3. Cams 72 secured to shafts 23 are provided to operate the actuating rods 67.

The operation of the safety brake is as 120 follows: Assuming that the elevator car is traveling downward at an excessive speed. The governor trips, and jaws 41 and 42 grip the governor rope 35, to bring it to a stop. Hitch 34 is withdrawn from carrier 51 and, as the car proceeds downwardly, rope 32 acting through lever arm 31 rotates shaft 27 against spring 30. The rotation of shaft 27 causes rotation of shafts 23 through gears 26 and 25. Cams 72 raise actuating rods 67 125 130

against springs 70. As rods 67 move upwardly, rollers 54 are brought into contact with cam surfaces 77 and rail 16, the pivotal connections between rollers 54 and rods 67 permitting the rollers to follow the cams. Since the car is still moving downwardly, rollers 54 ride up cam surfaces 77 on jaws 52 and 53 until they reach the stops 78. As the rollers move upwardly, jaws 52 and 53 move upwardly and outwardly on links 62, at the same time compressing springs 63. The parts are then in the positions shown in Figure 4 and the safety brake is applied. It will be noted that stops 78 act in the manner of brake shoes applied to rollers 54, which roll on the rail. The retarding force may be varied by adjusting the pressure of springs 63 and will remain substantially constant for any adjustment, independent of the condition of the rail or surface of stops 78. Were the retarding force to become greater, springs 63 would compress, thereby permitting jaws 52 and 53 to move away from rail 16 by swinging on links 62. Such movement would decrease the pressure acting to hold the rollers against the rail and consequently the retarding force.

In applying the safety, rope 32 rotates shaft 27 through 90° and when lever arm 31 has reached a horizontal position, rope 32, acting through hitch 34 draws the governor rope 35 through jaws 41 and 42 until the elevator is brought to a stop. When it is desired to reset the mechanism jaws 41 and 42 are manually released from rope 35 and latch 46 is reset. Hitch 34 is replaced in the releasing carrier 51 on the elevator. Movement of the car 10 in the up direction will return the rollers 54 to their lower position and thereby effect a release of the safety brakes.

Buffers 21, mounted in the elevator pit, are adapted to be engaged by bumpers 81 on the bottom of the elevator and to bring the car to a stop in the event that the elevator car continues to travel too far below its lowest landing level. Therefore if the safety brake be applied when the car reaches the point where its bumpers 81 engage the buffers double retardation results due to the simultaneous action of both the buffers and safety brakes to stop the car. As the retardation due to either the buffers or safety brakes acting singly is made the maximum commensurate with safety to passengers, the retardation due to both the buffers and safety brakes acting together brings about a dangerous condition. In order to prevent the simultaneous action of the safety brakes and buffers, the thickness of the guide rail 16 is reduced at 19 so as to effect a release of the safety brakes at the time or shortly before bumpers 81 come into contact with the buffers 21.

65 The reduced portion of the rail acts as a

guide for the safety brakes and guide shoes 18 after they pass from the rail of normal thickness if the car goes on to the buffers.

In the foregoing disclosure the safety brakes have been described as mounted on 70 the elevator car. However, safety brakes may be similarly used on the counterweight.

What is claimed is:

1. In an elevator system having a safety brake on a moving part adapted to cooperate with a stationary member throughout a portion of its path to stop the moving part and means for preventing the retardation by the safety brake in another portion of its path. 75

2. In an elevator system provided with a safety brake and a buffer, means for preventing simultaneous retardation by the safety brake and buffer. 80

3. In an elevator system, the combination of a safety brake on a moving part, a buffer mounted in the path of the moving part for stopping it, and means for preventing the simultaneous operation of the safety brake and buffer. 85

4. In an elevator system, the combination of an elevator car having a safety brake thereon, a second safety device comprising a buffer in the elevator pit, and means for rendering said safety brake on the car inactive at the time that the car engages said buffer. 90

5. In an elevator system, the combination of an elevator car having a safety device thereon adapted to be actuated for gripping 100 the elevator guide rail, a second safety device comprising a buffer in the elevator pit for stopping the car and means for preventing the simultaneous action of the two safety devices. 105

6. In an elevator system the combination of a guide rail having a normal thickness for a portion of its length and a reduced thickness for another portion of its length, and an elevator car having a safety brake adapted to grip the rail along the portion of normal thickness and incapable of gripping the rail along the portions of reduced thickness. 110

7. In an elevator system the combination of a guide rail having a normal thickness for a portion of its length and a reduced thickness for another portion of its length, an elevator car having a safety brake adapted to grip the rail along the portion of normal thickness and incapable of gripping the rail along the portions of reduced thickness, and buffers adapted to engage the elevator car at the part of its travel where the safety brake is incapable of gripping the rail. 115

8. In an elevator system including a guide rail for the elevator car, the combination of an elevator car having a safety brake thereon adapted to be actuated to grip the elevator guide rail, governor means operative to 120

125

130

actuate said safety brake into gripping engagement with the rail when the elevator is traveling downwardly above a predetermined speed, means for releasing the grip of said safety brake on the rail at a point adjacent to the bottom of the elevator hatchway, and buffers adapted to be engaged by the elevator at said point and bring the elevator to a stop independent of said safety brake.

9. In an elevator system the combination of a guide rail having a certain thickness along the path of the normal travel of the elevator car and a reduced thickness along 15 the path below the normal travel of the car, a safety brake on the car controlled by the speed of the car to grip the rail in the event of excessive speed of the car in the downward direction along the path of the normal 20 travel of the car and incapable of gripping the rail along the portion of the rail having a reduced thickness, and a buffer disposed in the elevator pit adapted to be engaged by the elevator car upon its passing below the 25 limit of normal travel.

10. In an elevator system, a guide rail having one thickness for a portion of its length, and a reduced thickness for another portion of its length.

30 11. In an elevator system, a guide rail having one thickness in the elevator hatchway along the normal path of travel of the elevator car, and having a reduced thickness for a distance below the normal path of 35 travel of the car.

12. A safety brake for elevators comprising a pair of jaws having cam surfaces, means for supporting said jaws on the elevator car on opposite sides of the elevator 40 guide rail, and a roller disposed between each jaw and the rail and adapted to be brought into engagement with the rail.

45 13. A safety brake for elevators comprising elements for engaging the sides of the elevator guide rail, means for actuating said elements into engagement with the rail, a jaw on each side of the guide rail between which jaws and the rail said elements are disposed, supporting means for said jaws comprising abutments and links arranged 50 substantially normal to the rails, said links being between the backs of the jaws and the abutments, and springs between said abutments and said jaws adapted to exert a 55 pressure upon the jaws substantially parallel with the rail, whereby a substantially constant retarding force of the safety brake is maintained.

60 14. A safety brake for elevators comprising a pair of rollers, a jaw disposed on each side of the rail and having an inclined cam surface between which cam surfaces and the rail said rollers are disposed, means for actuating said rollers along the cam surfaces 65 into engagement with the rail, and a stop

on said jaws at one end of said cam surfaces for limiting the movement of the rollers.

15. A safety brake for elevators comprising a pair of rollers, a jaw disposed on each side of the rail and having an inclined cam 70 surface between which cam surfaces and the rail said rollers are disposed, means for actuating said rollers along the cam surfaces into engagement with the rail, and a stop on said jaws at one end of said cam surfaces 75 for limiting the movement of the rollers along the cam, and resisting their rotation about their axes.

16. A safety brake for elevators comprising a pair of rollers, a jaw disposed on each 80 side of the rail and having an inclined cam surface between which cam surfaces and the rail said rollers are disposed, means for actuating said rollers along the cam surfaces into engagement with the rail, a stop on said jaws at one end of said cam surfaces for 85 limiting the movement of the rollers along the cam, and resisting their rotation about their axes, means for applying a pressure between the rollers and the rail, and means 90 for regulating the pressure to provide a substantially constant retarding force.

17. A safety brake for elevators comprising rollers for engaging the sides of the elevator guide rail, a jaw on each side of the rail having cam surfaces for guiding said rollers and holding them in engagement with the rail, rods connected with said rollers, and means for actuating said rods to move said rollers along the cam surfaces into 100 their engaged position.

18. A safety brake for elevators comprising rollers for engaging the sides of the elevator guide rail, a jaw on each side of the rail having cam surfaces for guiding said rollers and holding them in engagement with the rail, rods connected with said rollers, means for actuating said rods to move said rollers along the cam surfaces into their engaged position, and means for holding the 105 rollers out of engagement with the rail when the safety brake is released.

19. A safety brake for elevators comprising an abutment on each side of the elevator guide rail, a jaw disposed between each of said abutments and the rail and provided with a cam surface inclined upwardly toward the rail, a pair of links extending between each abutment and a jaw and arranged substantially at right angles with respect to the rail, springs between the upper ends of the jaws and the abutments arranged to exert a pressure on said jaws in a direction substantially parallel with the rail, rollers in the space between the cam 115 surfaces on the jaws and the rail, rods connected with said rollers and extending downwardly through said abutments, springs on the rods between said abutments and the lower ends of said rods operating on the 120

125 lower ends of said rods operating on the 130

rods to draw the rollers to the lower position between the jaws and the rail, and means adapted to raise said rods so as to actuate the rollers along said cam surfaces into engagement with the rail.

20. A safety brake for elevators comprising an abutment on each side of the elevator guide rail, a jaw disposed between each of said abutments and the rail and adapted to swing away from the rail upon the retarding force of the safety brake exceeding a predetermined amount.

21. A safety brake for elevators comprising

ing an abutment on each side of the elevator guide rail, a jaw disposed between each of 15 said abutments and the rail and provided with a cam surface inclined toward the rail, said jaws being adapted to swing away from the rail while maintaining the cam surfaces in the same angular relation with respect 20 to the rail, and rail engaging members disposed between said cam surfaces and the rails.

In testimony whereof, I have signed my name to this specification.

DAVID L. LINDQUIST.
